UNITED STATES PATENT OFFICE.

ADOLPH W. H. LENDERS, OF CEDAR RAPIDS, IOWA, ASSIGNOR, BY MESNE ASSIGNMENTS, TO PENICK & FORD, LTD., INCORPORATED, A CORPORATION OF DELAWARE.

FLUSHING SYSTEM FOR STARCH TABLES.

Application filed December 24, 1917. Serial No. 208,636.

To all whom it may concern:

Be it known that I, ADOLPH W. H. LENDERS, a citizen of the United States, residing at Cedar Rapids, in the county of Linn and State of Iowa, have invented certain new and useful Improvements in Flushing Systems for Starch Tables, of which the following is a specification.

My invention relates to the manufacture of starch and, more particularly, to the removal of starch from the starch tables over which, according to common practice, it is flowed for the purpose of eliminating gluten.

The primary object of the invention is to provide new and improved method of removing the table starch from the tables by flushing.

A further object is to automatically control the flushing operation so that flushing liquid in circulation will not become so heavy as to be ineffective and so that the resultant liquor will if desired have a determinable uniform density.

The invention consists in the new and improved arrangements, constructions and devices to be hereinafter described and claimed for carrying out the above stated objects and such other incidental objects as will be adverted to in the following description.

The invention is illustrated, in a preferred embodiment, in the accompanying drawings, wherein

Fig. 1 is a fragmentary end elevation of a bank of starch tables showing the piping, valves and fittings and other apparatus constituting an apparatus suitable for practicing the method of my invention.

Fig. 2 is a fragmentary longitudinal section of the bank of tables as shown in Fig. 1.

Fig. 3 is a diagrammatic view of the circulation tank, automatic valve and pump, and their pipe connections forming part of the flushing system.

In the installation shown there are four tables, or preferably, sets of tables, A; B, C and D, arranged one above the other on four different levels. The tables of each set are arranged alongside of one another and, preferably, the tables of each set in vertical alignment with those of the sets above and below the same.

60 is a flushing header arranged over the

upper ends of the tables A. The header 60 is provided with down spouts 61. The flushed starch liquor from tables A pass through spouts 62 to the upper ends of tables B. The flushed starch liquor from tables B passes through spouts 63 to tables C and the liquor flushed from tables C passes through spouts 64 to tables D. The flushed starch liquor from tables D passes through pipes 65 into a collecting pipe 66 which discharges into the circulation tank F. From tank F the liquor is pumped, by pump 67, through pipe 68 to header 60. 69 is a pipe through which the starch liquor in the circulation tank is discharged therefrom when it reaches a desired density. In the pipe 69 is arranged an automatically operated valve 70 which is opened and closed by any suitable mechanism in response to variations in density of the liquor in the circulation tank. The valve 70, as indicated in Fig. 3, may be of the butterfly type, its shaft 71 having 75 fixed thereto a counterweighted lever 72 to which is attached a cord 73 running over pulleys 74, 74, and having secured to its other end a float 75 arranged within the circulation tank F. When the starch in the tank F becomes sufficiently dense float 75 will rise, causing the valve to move from its closed position, shown in the full lines in Fig. 3, to its open position, shown in the dotted lines. The pipe 68 leads to one end of header 60. A fresh water supply pipe 76 leads to the other end of the header, this pipe being provided with a valve 77. The header is provided with shut-off valves 78 arranged preferably between each table. By this arrangement the flushing of the tables may be commenced by use of water which will be used until enough starch liquor has collected in the circulation tank to permit the pump 67 to be started and this starch liquor used as a flushing medium. 79 is a valve in pipe 68 above the pump 67.

After the starch has been deposited on the tables and the gluten drained off, the starch is removed from the tiers of tables, a tier at a time, beginning with the left hand tier, as shown in Fig. 1. The left hand valve 78, referring to the same figure, will be closed and valve 77 in the water supply pipe 76 opened. The water will flow from pipe 76 into the header 60 as far as

the first valve 78. From header 60 it is discharged through spouts 61 upon the upper end of table A. Water flows in a continuous stream over the upper surface of the starch on table A, collecting, as it goes, a certain amount of the starch which is carried with it through spouts 62 to table B, over table B and through spouts 63 to table C, over table C through spouts 64 to table D, and thence through branch pipes 65 into the collecting pipe 66 and then to the circulation tank F. The starch on the tables contains a considerable amount of water, usually about fifty per cent, and this flows off from the tables as the starch is eroded. As soon as the circulation tank F has collected a certain amount of starch liquor the fresh water valve 77 may be closed and the flushing operation carried on with this starch liquor which at first will be relatively light. The starch liquor is pumped from tank F by pump 67 through pipe 68 to the header 60. All of the valve 78 will now be opened (that is, all provided that the starch has not already been completely flushed from the left hand tier of tables valve 77 opened to the extent required) and the delivery of the flushing liquid to the particular tables operated upon controlled by the valves 96 in the flushing spouts 61. As soon as one tier of tables is flushed the valve 78 to the right of that table may be closed and the valves 96 over the next of the tables A be opened.

When the density of the starch in circulation tank F reaches the desired point, the float 75 will rise causing valve 70 to be opened, thus permitting the discharge of a certain amount of the starch liquor from

the circulatory system. The operation of the apparatus can be so adjusted as to discharge just enough of the starch liquor, at the right density, to maintain a volume of liquid in the tank and in circulation at a density not too great for the flushing operation in progress; valve 77 being adjusted so that the quantity of water added substantially equals the quantity of heavy starch liquor withdrawn through pipe 69.

The starch liquor which is run off through pipe 69 may be employed in the manufacture of starch products of a character to require the starch in liquid form or the starch may be separated from the water by any suitable apparatus.

I claim:

1. Method of removing starch from settling tables which consists in maintaining a quiet flow of a flushing liquid over the upper surface of the starch to gradually thin down the starch body until it has been removed.

2. Method of removing starch from settling tables which consists in repeatedly circulating a flushing liquid over the upper surface of the starch to gradually thin the starch down until it has been removed, and maintaining the flushing liquid at a substantially constant density throughout the operation.

3. The method of claim 1 in which the liquid is circulated repeatedly over the body of starch and is kept from exceeding a workable density by removing portions of it from time to time and replacing the same with a lighter liquid.

ADOLPH W. H. LENDERS.
